C. STEENSTRUP

METHOD OF MANUFACTURING PACKINGS FOR ROTATING SHAFTS

Original Filed Feb. 24, 1920

Fig.1.

Fig.2.

Fig.3.

Inventor:
Christian Steenstrup,
by *Albert G. Davis*
His Attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

METHOD OF MANUFACTURING PACKINGS FOR ROTATING SHAFTS.

Application filed February 24, 1920, Serial No. 360,980. Renewed November 19, 1923.

To all whom it may concern:

Be it known that I, CHRISTIAN STEENSTRUP, a citizen of the United States, residing at Schenectady, in the county of Schenectady, State of New York, have invented certain new and useful Improvements in Methods of Manufacturing Packings for Rotating Shafts, of which the following is a specification.

10 The present invention relates to packings such as are used to prevent leakage between a rotating shaft and an adjacent wall through which the shaft passes and particularly to packings of the type comprising a plurality of thin-edged annular teeth or projections which are carried by the rotating member and pack against the surface of the adjacent wall, or which are carried by the wall and pack against the outer surface of 20 the shaft. Packings of this character are well known and are termed labyrinth or cellular packings.

The object of the present invention is to provide an improved method of manufacturing packings of the type referred to which is economical to carry out, and by means of which a large number of thin-edged annular teeth or projections may be provided in a comparatively short space.

30 A further object of the invention is to provide an improved method in which all the operations are of a simple character and may be carried out by the ordinary workman without the use of special tools, whereby highly skilled labor will not be required.

For a consideration of what I believe to be novel and my invention, attention is directed to the accompanying description and the claims appended thereto.

40 In the accompanying drawing, Fig. 1 is a side elevation partly in section, of a packing element embodying my invention, and Figs. 2 and 3 are similar views of modifications.

45 Referring to the drawing, 5 in each figure indicates a section of shaft which may be, for example, a section of the shaft of an elastic fluid turbine at about the point where it passes through the turbine shell or casing. Suitably fixed on shaft 5, as by shrinking thereon, is a sleeve 6 which carries annular thin-edged teeth 7 which, as is well understood, would, when assembled in

the machine, pack against the adjacent wall through which the shaft 5 passes.

55 In accordance with the method shown in Fig. 1, I take a strip of metal which is L-shaped in section, one part forming the thin-edged teeth 7 and the other part 8 forming engaging and spacing means, and I wind the same spirally on sleeve 6 at the same time winding on top of part 8 a holding piece or ribbon 9. The L-shaped strip and the holding piece 9 may be wound on sleeve 6 at the same time either manually 60 by means of a suitable winding machine, or by other suitable means, and after being wound thereon to form a packing member of the desired length, the L-shaped strip and holding piece are fastened together and 65 to sleeve 6 by fusion of metal as by welding, brazing, or the like, or by other suitable means.

70 By the foregoing arrangement I obtain a packing element which is very simple to manufacture and in which the annular teeth 7 may be made as close together and as thin as found desirable, the part of the L-shaped strip which forms the thin-edged teeth 7 being finished to the desired thickness prior to being wound on sleeve 6.

75 Instead of utilizing an L-shaped strip as shown in Fig. 1, I may utilize a U-shaped strip as shown in Fig. 2, and in this case I preferably turn a spiral groove 10 in the outer surface of sleeve 6, after which I wind 80 a strip 11 which is U-shaped in cross-section into groove 10, at the same time winding a holding strip 12 between the legs of the U-shaped strip to fasten it in the spiral groove. After being positioned in spiral groove 10, U-shaped strip 11 and holding strip 12 may be suitably welded, brazed or otherwise fastened together and to sleeve 6.

85 Referring now to Fig. 3 an arrangement similar to that shown in Fig. 2 is illustrated except that the strip which is wound in the spiral grooves indicated at 13 is L-shaped instead of U-shaped in cross-section, the method of making the packing element of 90 Fig. 3 is exactly similar to that just described in connection with Fig. 2.

95 In accordance with the provisions of the patent statutes, I have described my improved method in connection with the steps 100 which I now prefer for carrying it out, but

it will be understood that the specific steps described are only illustrative and that the method may be carried out by such steps as come within the terms of the appended 5 claims.

What I claim as new and desire to secure by Letters Patent of the United States, is:—

1. The method of manufacturing a packing element comprising a plurality of annular, radially extending teeth which comprises taking a cylinder, winding on one of its surfaces an angular strip and a holding piece, and fastening the strip and piece together and to the cylinder.
15. 2. The method of manufacturing a packing element comprising a plurality of annular, radially extending teeth which comprises taking a cylinder, winding on one of its surfaces simultaneously, an angular strip 20 and a holding ribbon, and then permanently fastening the strip, ribbon, and cylinder together.
3. The method of manufacturing a packing element comprising a plurality of annular, radially extending teeth which comprises taking a cylinder, cutting a continuous spirally extending groove in one of its surfaces, winding an angular strip in said 25 groove, and fastening said strip to said cylinder.
30. 4. The method of manufacturing a packing element comprising a plurality of annular, radially extending teeth which comprises taking a cylinder, cutting a continuous spirally extending groove in one of its surfaces, winding an angular strip and a holding piece simultaneously in said groove, and fastening said strip, piece and cylinder together.
35. 40. 5. The method of manufacturing a packing element comprising a plurality of annular, radially extending teeth, which comprises taking a cylinder, spirally winding thereon simultaneously a U-shaped strip and a holding piece between the legs of said strip, and fastening said strip, piece, and cylinder together.

6. The method of manufacturing a packing element comprising a plurality of annular, radially extending teeth which comprises taking a cylinder, cutting a continuous, spirally extending groove in one of its surfaces, winding in said groove a U-shaped strip and a holding ribbon located between the legs of said strip, and fastening said strip, ribbon and cylinder together.

7. The method of manufacturing a packing element which comprises providing a carrying member having grooves in one of its surfaces, placing thin metal strip material edgewise in the grooves, and permanently fastening it therein by fusion of metal.

8. The method of manufacturing a packing element which comprises providing a carrying member having a continuously extending groove in one of its surfaces, and fastening a continuous strip of thin metal edgewise in the groove.

9. The method of manufacturing a packing element which comprises providing a carrying member having a continuously extending groove in one of its surfaces, and fastening a continuous strip of thin metal edgewise in the groove by fusion of metal.

10. The method of manufacturing a packing element which comprises providing a carrying member having grooves in one of its surfaces, placing thin metal strip material edgewise in the grooves, fastening it 80 therein in a temporary manner, and then permanently fastening it therein by fusion of metal.

11. The method of manufacturing a packing element which comprises providing a carrying member having a continuously extending groove in one of its surfaces, fastening a strip of thin metal edgewise in said groove in a temporary manner, and then permanently fastening it therein by fusion 90 of metal.

In witness whereof, I have hereunto set my hand this 20th day of February, 1920.

CHRISTIAN STEENSTRUP.
